UNITED STATES PATENT OFFICE

RICHARD E. MURPHY, OF PITTSBURGH, PENNSYLVANIA, ASSIGNOR TO SULLIVAN MACHINERY COMPANY, A CORPORATION OF MASSACHUSETTS

DRILLING MECHANISM

Application filed May 8, 1928, Serial No. 274,821. Renewed March 30, 1931.

This invention relates to drilling mechanisms and more particularly, but not exclusively, pertains to a rotary coal drilling mechanism especially adapted to use in drilling "shot" or blast holes in the coal face.

An object of this invention is to provide an improved drilling mechanism and more particularly to provide an improved feeding means for such a mechanism. Another object is to provide improved feeding means for a drilling tool having embodied therein mechanism for permitting the initial positioning of the tool to facilitate the starting of a hole. Yet another object is to provide an improved tool feeding mechanism of the differential screw type having embodied therein a slip motion or sliding connection whereby the drilling tool may be manually slid forwardly in position at the coal face independently of the feed screw mechanism to facilitate positioning of the tool during starting of a hole. These and other objects of this invention will however subsequently more fully appear as the description proceeds.

In the accompanying drawings there is shown for purposes of illustration one form which the invention may assume in practice.

In these drawings,

Fig. 1 is a central longitudinally extending vertical sectional view illustrating a drilling mechanism having the invention embodied therein.

Figs. 2 and 3 are detail sectional views taken respectively on lines 2-2 and 3-3 of Fig. 1.

Fig. 4 is a detail view of the improved slip motion or sliding connection showing the parts in a different position from that shown in Fig. 1.

In this illustrative construction the improved means for initially positioning the drilling tool for facilitating the starting of a hole is shown incorporated in a drilling mechanism of the same general type as that described in the copending application of one Morris P. Holmes, Serial No. 255,754, filed February 20, 1928. This drilling mechanism comprises an adjustable tubular supporting arm 1 having arranged concentrically therein a transmission shaft 2 operatively connected

to a usual driving motor (not shown). The forward end of the shaft 2 is journaled in a ball bearing 3 supported within a swivel frame or bearing bracket 4 having a sleeve portion 5 projecting within and rigidly fixed to the tubular arm 1. Swivelly mounted on the swivel bracket 4 is a drill generally designated 6 and comprising a plural part casing or housing 7 provided with an annular flange 8 rotatably mounted in a bore 9 formed within the swivel bracket 4. Also secured to the casing 7 as by screws 10 is a swivel plate 11 having a ring or annular flanged portion 12 rotatably mounted in a bore 13 formed in the swivel bracket 4 and arranged in axial alignment with the bore 9. It will thus be seen that the drill 6 may be bodily swung relative to the swivel bracket 4 about an axis perpendicular to the axes of the transmission shaft 2 and the tubular supporting arm 1. In order to secure the drill 6 to the swivel bracket 4 in its different adjusted positions a manually operable clamping screw 14 is provided, this screw being threadedly connected to the bracket 4 and engaging the bottom of a peripheral groove 15 formed on the swivel plate 11.

As illustrated, the transmission shaft 2 has fixed thereto a bevel pinion 16 meshing with a bevel ring gear 17 rotatably mounted on a ball bearing 18 suitably supported within the drill casing. The bevel ring gear 17 meshes with a bevel gear 19 fixed to a shaft 20 journaled in ball bearings 21 suitably carried by the drill casing and this shaft also has fixed thereto spur gears 22 and 23, these spur gears constituting the driving elements for the rotating and feeding mechanisms for the drilling tool. As shown the spur gear 22 meshes with a spur gear 24 rotatably mounted on a bearing sleeve 25. This spur gear 24 has a sleeve portion carrying clutch plates 26 which are interleaved with clutch plates 27 carried by a rotatable driving sleeve or spider 28. This drive sleeve is journaled in ball bearings 29 and 30 suitably supported within the drill casing. Herein supported on the drive sleeve 28 and in turn supporting the bearing sleeve 25 is a retaining sleeve or bushing 31.

interposed between the adjacent ends of the clutch plate and the bearing 30. Encircling the drive sleeve 28 and slidably mounted thereon is a clutch applying member 32 normally held in clutch applying position by a coil spring 33 encircling the drive sleeve 28 and reacting against a sleeve 34 abutting against an adjustable collar 35 threadedly connected to the rotatable drive sleeve 28. As shown the rotatable drive sleeve 28 has inwardly projecting keys 36 engaging longitudinal flutes or keyways 37 formed on the periphery of a tool carrying member herein a tubular driving sleeve or shaft 38. Threadedly connected to the sleeve 38 at its forward end is a tool chuck 39 having formed therein a polygonal socket 40 for receiving the square shank of the drilling tool 41. Clamped in position against the forward end of the sleeve 38 by the chuck casing is a stop plate 42 for the drilling tool.

As shown, the gear 23 meshes with a spur gear 45 having a different tooth ratio from the gear 24 and rotatably mounted on a bearing sleeve 46. This gear 45 has a sleeve portion which carries clutch plates 47 which are interleaved with clutch plates 48 carried by a drive sleeve or tubular drive member 49. This sleeve member 49 is keyed at 50 to a member 51 in turn keyed at 52 to a sleeve or tubular drive member 53, the sleeve 49 being mounted on the member 53. The tubular drive sleeve 53 is journaled in ball bearings 54 and 55 suitably carried within the drill casing. The member 51 is interposed between the clutch plates and the bearing 54 and forms a support for the bearing sleeve 46. As illustrated the tubular member 53 is provided with a radial flange 56 interposed between the inner race of the contiguous ball bearings 55 and a ball thrust bearing 57. Slidably mounted on the sleeve 49 is a clutch applying member 58 normally held in clutch applying position by a coil spring 59 encircling the sleeve 49 and reacting against a sleeve 60 engaging an adjustable collar 61 threadedly connected to the sleeve 49. The mechanism for releasing the drive clutch 26, 27 and the feed clutch 47, 48 is substantially the same as that described in the copending application mentioned above and since it does not specifically enter into this invention further description is deemed unnecessary.

In accordance with this illustrative form of the invention the tubular member or drive sleeve 38 has formed thereon at its rear end a feed nut 62 threadedly connected to a feed screw 63 extending centrally within the driving sleeve 38, this feed screw being adapted to move inwardly and outwardly with respect to the drive sleeve 38 as will hereinafter be described. Keyed at 64 to a rearward extension 65 formed integral with the feed screw 63 is a member 66 held in position by a lock nut 67 threadedly connected to the extension

65. This member 66 has laterally projecting keys 68 engaging longitudinal flutes or keyways extending throughout a portion of the bore within the drive sleeve 53, as clearly shown in Fig. 1. The rear end of the drive sleeve 53 is closed by a cap member 69 against which the rear end of the member 66 is adapted to abut during the feeding operation of the mechanism as will later be described. This cap member 69 is provided with a recess 70 within which the lock nut 67 is adapted to enter when the feed screw is in its retracted position.

In the operation of the improved drilling mechanism the tubular supporting arm is adjusted in a manner clearly described in the copending application mentioned above and the drill suitably positioned adjacent the coal face. The operator then inserts the drilling tool 41 within the chuck 39 and then grasps the chuck casing and moves the drilling tool forwardly until the cutting bit engages the coal face, the tubular drive sleeve 38, the feed screw 63, and the member 66 sliding axially relative to the sleeve 28 and tubular member 53. After the drilling tool of the drill is positioned adjacent the coal face, the driving motor is started and the operator then suitably manipulates the clutch controlling means thereby moving the clutch members 32 and 58 into released position, the coil springs 33 and 59 automatically applying the clutches. Since the gear 45 rotates at a speed slower than the gear 24 the tubular drive member 53 together with the feed screw 63 are rotated at a speed slower than the tubular drive member 38 and as a result the feed screw 63 is fed slowly rearwardly from the position shown in Fig. 1 until the member 66 engages the cap 69 as shown in Fig. 4. When the member 66 engages this cap axial rearward movement of the feed screw is prevented and consequently, since the tubular drive sleeve 38 rotates at a speed slightly faster than the feed screw 63, the feed nut 62 moves axially forwardly relative to the feed screw thereby feeding the drilling tool into the coal at a relatively slow drilling speed. After the hole is completed or if it is desired to change the drilling tool the operator releases the clutch applying member 32 while the clutch 47, 48 remains applied. Resultantly the tubular drive sleeve 53 together with the feed screw 63 are rotated relative to the then stationary feed nut 62 and consequently the feed screw moves forwardly axially at a relatively high speed from the position shown in Fig. 4 to the position shown in Fig. 1. The feed screw and the tubular drive sleeve 38 thereupon turn together with no axial feeding movement. The operator then grasps the chuck 39 and manually slides the tubular drive member 38, feed screw 63, and member 66 rearwardly into their initial starting position.

tion, these parts being shoved rearwardly until the member 63 engages the cap 69.

As a result of this invention it will be noted that an improved rotary coal drill is provided having improved screw operated feeding means of the differential type and having embodied therein a slip motion or sliding connection whereby the drilling tool may be initially positioned adjacent the coal face and as a result the starting of a hole is clearly facilitated, it having been found that if the drilling tool were rotated during the starting of a hole the drilling tool wobbles considerably and the tool is deflected from its desired location. Furthermore it will be noted that improved means is provided for initially positioning the drilling tool thereby facilitating the starting of a hole, the positioning means being of an exceedingly simple character and which may be applied to a drilling mechanism of standard construction with a minimum of change and expense. These and other advantages and uses of the invention will be clearly apparent to those skilled in this art.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. In a drilling mechanism, a drilling tool, and feeding means therefor including coacting relatively rotatable feeding elements, and rotating means for one of the same including means permitting free axial movement of said feeding elements relative to said rotating means to initially position said tool.

2. In a drilling mechanism, a drilling tool, and feeding means therefor including coacting relatively rotatable feeding elements, and rotating means for one of the same including means permitting free axial movement of said feeding elements relative to said rotating means to initially position said tool, said rotating means thereafter being operative to effect feeding movement of said tool.

3. In a drilling mechanism, a drilling tool, and feeding means therefor including coacting relatively rotatable feeding elements, and rotating means for one of the same, said rotating means permitting free axial movement of said feeding elements relative to the same to initially position said tool.

4. In a drilling mechanism, a drilling tool, and feeding means therefor including coacting relatively rotatable feeding elements, and rotating means for one of the same, said rotating means permitting free axial movement of said feeding elements relative to the same to initially position said tool, said feeding element and rotating means thereafter be-

ing operative to effect feeding movement of said tool.

5. In a drilling mechanism, a drilling tool, and power operated feeding means therefor including coacting relatively rotatable feed screw and nut elements, and rotating means for one of said elements including means permitting free axial movement of said screw and nut elements relative to said rotating means to initially position said tool during starting of a hole. 70

6. In a drilling mechanism, a drilling tool, and power operated feeding means therefor including coacting relatively rotatable feed screw and nut elements, and rotating means for one of said elements including means permitting free axial movement of said screw and nut elements relative to said rotating means to initially position said tool during starting of a hole, said rotating means and screw and nut elements thereafter being operative to effect feeding movement of said tool. 80

7. In a drilling mechanism, a drilling tool, and power operated feeding means therefor including coacting relatively rotatable feed screw and nut elements, and rotating means for one of the same, said rotating means permitting free axial movement of said feeding element rotated thereby and said other feeding element relative thereto to initially position said tool during starting of a hole. 90

8. In a drilling mechanism, a drilling tool, and power operated feeding means therefor including coacting relatively rotatable feed screw and nut elements, and rotating means for one of the same, said rotating means permitting free axial movement of said feeding element rotated thereby and said other feeding element relative thereto to initially position said tool during starting of a hole, said rotating means and said screw and nut elements thereafter being operative to effect feeding movement of said tool. 100

9. In a drilling mechanism, a drilling tool, and power operated feeding means therefor including coacting relatively rotatable feed screw and nut elements, and rotating means for one of the same including a sliding connection between the element rotated by said rotating means and the latter permitting free axial movement of said feeding elements relative to said rotating means to initially position said tool during starting of a hole. 110

10. In a drilling mechanism, a drilling tool, and power operated feeding means therefor including coacting relatively rotatable feed screw and nut elements, and rotating means for one of the same including a sliding connection between the element rotated by said rotating means and the latter permitting free axial movement of said feeding elements relative to said rotating means to initially position said tool during starting of a hole, said rotating means and screw and nut 120

125

130

elements thereafter being operative to effect feeding movement of said tool.

11. In a drilling mechanism, a drilling tool, and power operated feeding means therefor including coacting relatively rotatable feed screw and nut elements, and rotating means for said screw including means permitting free axial movement of said screw and nut relative to said rotating means to effect initial positioning of said tool during starting of a hole.

12. In a drilling mechanism, a drilling tool, and power operated feeding means therefor including coacting relatively rotatable feed screw and nut elements and rotating means for said elements for effecting rotation of the same at different speeds, said rotating means including means for permitting free axial movement of said feeding elements relative to said rotating means to effect initial positioning of said tool during starting of a hole.

13. In a drilling mechanism, a drilling tool, and power operated feeding means therefor including coacting relatively rotatable feeding elements, and rotating means therefor for effecting rotation thereof at different speeds, said rotating means including means permitting free axial movement of said feeding elements relative thereto to effect initial positioning of said tool during starting of a hole.

14. In a drilling mechanism, a drilling tool, power operated reversible feeding means for said tool for feeding the latter forwardly and rearwardly including an axially movable feeding element, power operating mechanisms therefor, and a tool carrying element movable axially relative to said feeding element, and means permitting free axial movement of said feeding element and said tool carrying element, relative to the power operating mechanism of the former to effect initial positioning of said tool upon starting of a hole.

15. In a drilling mechanism, a drilling tool, and feeding means therefor including coacting feeding elements having relative axial movement, actuating means for one of said feeding elements, a tool carrying member movable axially with one of said feeding elements and relative to the other feeding element, and means permitting free axial movement of said tool carrying member and that feeding element relative to which said tool carrying member is movable bodily relative to said actuating means to initially position said tool.

16. In a drilling mechanism, a drilling tool, and feeding means therefor including coacting feeding elements having relative axial and relative rotative movements, rotating means for one of said elements, a tool carrying member movable axially with one of said feeding elements, and means permitting

free axial movement of said feeding elements relative to said rotating means while the coacting relation of said feeding elements is maintained to initially position said tool.

17. In a drilling mechanism, a drilling tool, and feeding means therefor including coacting feeding elements having relative axial and relative rotative movements, rotating means for one of said elements including a final rotating element, a tool carrying member movable axially with one of said feeding elements and relative to said final rotating element, and means including a sliding connection between one of said feeding elements and said rotating element permitting free axial movement of said feeding elements relative to said rotating means while the coacting relation of said feeding elements is maintained to initially position said tool.

18. In a drilling mechanism, a drilling tool, and feeding means therefor including coacting relatively rotatable screw and nut elements, a tool carrying member movable axially with one of said feeding elements, rotating means for the other of said feeding elements, and means permitting free axial movement of said latter feeding element bodily relative to its rotating means to initially position the tool.

19. In a drilling mechanism, a drilling tool, and feeding means therefor including coacting relatively rotatable screw and nut elements, a tool carrying member movable axially with one of said elements and relative to the other element, rotating means for said feeding elements including a final rotation element, and means including a sliding connection between one of said feeding elements and said final rotation element permitting free axial movement of said feeding elements bodily relative to said rotating element to initially position the tool.

20. In a drilling mechanism, a drilling tool, feeding means therefor including coacting relatively rotatable feeding elements, rotating means for said feeding elements, and means permitting free axial movement of one of said feeding elements relative to its rotating means to initially position said tool.

21. In a drilling mechanism, a drilling tool, and feeding means therefor including coacting relatively rotatable screw and nut elements, means for effecting rotation of said screw and nut elements at different speeds to effect axial movement of one of the same relative to the other, and means permitting free axial movement of one of said feeding elements relative to its rotation means to initially position the tool.

22. In a drilling mechanism, a drilling tool, and feeding means for said tool including coacting relatively rotatable screw and nut elements, a tool carrying member connected to one of said feeding elements and movable axially relative to the other, means

for rotating said feeding elements at different speeds to effect axial movement of said tool carrying member, and a sliding connection between said screw element and its rotation means permitting free axial movement of said screw element to initially position the tool.

23. In a drilling mechanism, a drilling tool, rotation means for said tool including a rotating member and a member slidably connected therewith and rotatable thereby, and feeding means for sliding said members axially to effect feeding of the tool including cooperating feeding elements one of which is connected to said sliding member, rotating means for the other feeding element, and a sliding connection between said feed element rotating means and said latter feeding element.

24. In a drilling mechanism, a drilling tool, rotation means for said tool including cooperating rotating members having relative axial movement, and feeding means for the tool including cooperating feeding elements one of which is connected to one of said relatively axially movable members, rotating means for the other feeding element, and a sliding connection between said feed element rotating means and said latter feeding element.

25. In a drilling mechanism, a drilling tool, rotation means for said tool including a rotating member and a tubular member having splined connection with the rotating member and movable axially therethrough, and feeding means for the tool including a rotating tubular member, a sliding member having splined connection therewith and rotatable thereby, said member being movable axially relative thereto during rotation thereof, and cooperating relatively rotatable feeding elements, one connected with said tubular rotating feed member and the other connected with said sliding feed member.

26. In a drilling mechanism, a drilling tool, rotation means for said tool including a rotating member, a tubular member having splined connection with the rotating member and movable axially therethrough, and feeding means for the tool including a rotating tubular member, a sliding member having splined connection therewith and rotatable thereby, said member being movable axially relative thereto during rotation thereof, and cooperating relatively rotatable feeding elements, one connected with said tubular rotating feed member and the other connected with said sliding feed member, said feeding elements and said sliding feed member being movable axially relative to said tubular rotating feed member to permit bodily movement of the tool initially to position the latter.

27. In a drilling mechanism, a drilling tool, rotation means for said tool including

a rotating member, a tubular member having a splined connection with the rotating member and movable axially therethrough, and feeding means for the tool including a rotating tubular member, a sliding member having splined connection therewith and rotatable thereby, said member being movable axially relative thereto during rotation thereof, and cooperating relatively rotatable feed screw and nut feeding elements, one connected with said tubular rotating feed member and the other connected with said sliding feed member.

28. In a drilling mechanism, a drilling tool, rotation means for said tool including a rotating member, a tubular member having splined connection with the rotation member and movable axially therethrough, and feeding means for the tool including a rotating tubular member, a sliding member having splined connection therewith and rotatable thereby, said member being movable axially relative thereto during rotation thereof, and cooperating relatively rotatable feed screw and nut feeding elements, one connected with said tubular rotating feed member and the other connected with said sliding feed member, said feeding elements and said sliding feed member being movable axially relative to said tubular rotating feed member to permit bodily movement of the tool initially to position the latter.

29. In a drilling mechanism, a drilling tool and feeding means for said tool including coacting feeding elements having relative axial movement, actuating means for one of said feeding elements, a tool carrying member movable axially with one of said feeding elements and relative to the other feeding element, and means permitting free axial movement of said tool carrying member and that feeding element relative to which said tool carrying member is movable, bodily relative to said actuating means initially to position said tool, one of said feeding elements having axial movement in a rearward direction after such positioning and prior to the feeding of the tool.

30. In a drilling mechanism, a drilling tool and feeding means for said tool including coacting screw and nut feeding elements having relative axial and relative rotative movements, rotating means for one of said elements, a tool carrying member movable axially with said other feeding element, and means permitting free axial movement of said feeding elements relative to said rotating means while the coacting relation of said feeding elements is maintained initially to position said tool, one of said feeding elements moving rearwardly a predetermined distance after such initial positioning and prior to the feeding of said tool.

31. In a drilling mechanism, a drilling tool, rotating means for said tool including a

- rotating member, and a tubular member having splined connection therewith and movable axially relative thereto, and feeding means for said tool including a feed member carried by said tubular member and a coacting feed member telescopically arranged within said tubular member, said feed members being movable freely axially with said tubular member initially to position said tool.
32. In a drilling mechanism, a drilling tool, rotating means for said tool including a rotating member and a tubular member having splined connection therewith and movable axially relative thereto, and feeding means for said tool including a rotatable tubular member, a feed member carried by said first tubular member, and a coacting feed member rotatable with said second tubular member and telescopically arranged within said tubular members, said feed members being movable freely axially relative to said second tubular member initially to position said tool.

In testimony whereof I affix my signature.

RICHARD E. MURPHY.
